UNITED STATES PATENT OFFICE.

GUGLIELMO CAMILLI, OF PITTSFIELD, MASSACHUSETTS, ASSIGNOR TO GENERAL ELECTRIC COMPANY, A CORPORATION OF NEW YORK.

TRANSFORMER.

Application filed October 10, 1928. Serial No. 311,639.

My invention relates to transformers and more particularly to transformers having concentric cylindrical windings. When a transformer is in operation, the main magnetic flux is substantially confined to the core. The action of the primary and secondary currents also produces a leakage flux between the two windings. This leakage flux, after flowing between the windings, returns through the easiest path which it can find and the return path for a large part of the leakage flux often includes magnetic material near the core and windings such as the core clamping structure and the metal casing in which the transformer may be enclosed. The flux in these adjacent magnetic parts results in magnetic losses and decreased efficiency of the transformer and it is the general object of the invention to provide an improved arrangement for controlling and reducing the external leakage flux and the magnetic losses caused by it.

The invention will be better understood from the following description taken in connection with the accompanying drawings in which Fig. 1 is a perspective view of a shell type transformer provided with means for reducing the external leakage flux; Fig. 2 is a similar view of a core type transformer; Fig. 3 is a similar view of a three phase core type transformer and Fig. 4 is a view of a transformer like that shown in Fig. 1 but with a different arrangement of windings.

Like reference characters indicate similar parts in the different figures of the drawings.

The transformer shown in Fig. 1 is of the shell type with a magnetic core 10 having a central winding leg and two outer legs joined at their ends by yokes. The central winding leg is surrounded by the two windings 11 and 12. The main magnetic flux is substantially confined to the core. The currents in the two windings produce a leakage flux through the space between them and returning through the easiest path which it can find. The return path for a considerable part of the leakage flux often includes magnetic material outside of the core and windings. This magnetic material may include the core clamping structure, the metal casing which may enclose the transformer and other adjacent magnetic parts. Under these conditions, the magnetic losses in these parts may be considerable so as to reduce appreciably the efficiency of the transformer. These losses ap-

pear as heat, too, and provision for dissipating this heat in addition to that from the transformer itself must be made or excessive temperatures may result.

As shown in Fig. 1, the leakage flux is largely prevented from leaving the space between the two windings and reaching adjacent magnetic material by conductive members 13 connected by conductors 14 to form closed circuits close to the ends of the windings and in front of both ends of the space between the windings. There are four of the conductive members 13, two at each end of the outer winding and extending along and close to the ends of this winding on opposite sides of the core. The ends of each member 13 are connected by conductors 14 to the ends of the member 13 which is at the same end of the winding 12 and on the opposite side of the core, the conductors 14 extending around the outer edge of the core to avoid a short circuited turn around the central winding leg of the core. It is apparent that no substantial amount of leakage flux can leave the space between the two windings except through the core under the conductors 14. Any magnetic material near the core and windings is thus effectively shielded and protected. It is considered that the best results will be obtained in most cases if the conductive members 13 extend along the outer face of the winding 12 and near its ends, the members 13 being as close to the winding as is practicable with the necessary insulation between them.

The conductive members 13 and the conductors 14 connecting them around the outer edge of the core are shown in Fig. 2 as applied to a core type transformer. The core 10 has two winding legs, each surrounded by two windings 11 and 12. This core has only a single opening and each set of windings passes through the core only once so that only one member 13 is necessary at each end of each of the outer windings 12, the two ends of each member 13 being at opposite sides of the opening through the core and connected together by a conductor 14. A single conductor 14 for two of the members 13 may be used if desired.

The invention is shown in Fig. 3 as applied to a three phase core type transformer. The core 10 of this transformer has three winding legs, each leg being surrounded by two windings 11 and 12. The set of windings on the central winding leg passes through the

core twice so that two members 13 connected by conductors 14 are necessary at each end of this set of windings. The set of windings on each of the outer winding legs passes 5 through the core only once so that only one member 13 with its ends connected by a conductor 14 is necessary at each end of each of these sets of windings.

The transformer shown in Fig. 4 is similar to that shown in Fig. 1 except that the winding 11 is formed in two concentric spaced sections. The winding 12 is interposed concentrically between the two sections of the winding 11 and spaced from each of those 10 sections. With this arrangement, the leakage flux is induced in the two spaces inside and outside of the winding 12 and between that winding and the two sections of the winding 11 and it is induced in opposite directions at any instant in these two spaces. Not all of the flux in either of these spaces, however, may return through the other space. Some of the flux tends to leave the windings and return through the easiest outside path as 15 has already been explained. The conductive members 13 connected by the conductors 14 largely reduces the outer magnetic field as in the case of the transformer shown in Fig. 1. Some of the magnetic flux also tends to return inside of the inner section of the winding 11 and much of this flux would enter the central winding leg crosswise of its laminations where it would cause excessive losses. Conductive members 15 are therefore provided 20 near both ends of the inner section of the winding 11, the two members 15 at each end being connected into a closed circuit by conductors 14 passing around the outer edge of the core. This closed circuit will obviously 25 prevent any substantial amount of flux from returning inside the inner section of the winding 11 so that nearly all the leakage flux will be confined to a path through the two spaces next to the winding 12.

40 The invention has been explained by describing and illustrating its application to various forms of transformers and it will be apparent that various further changes and

modifications may be made without departing from the scope of the invention as defined in 50 the appended claims.

What I claim as new and desire to secure by Letters Patent of the United States, is:

1. A transformer including a core having a winding leg, two spaced concentric windings 55 surrounding said winding leg, and a conductive member extending along and close to an end of the outer of said windings, the ends of said conductive member being connected to form a closed circuit in front of the space 60 between said windings.

2. A transformer including a core having a winding leg, two spaced concentric windings surrounding said winding leg, and a conductive member extending along and close to an end of the outer of said windings on each side 65 of said core, said conductive members being connected around the outer edge of said core to form a closed circuit in front of the space between said windings. 70

3. A transformer including a core having a winding leg, two spaced concentric windings surrounding said winding leg, and a conductive member extending along and close to each end of the outer of said windings on each 75 side of said core, said conductive members being connected around the outer edge of said core to form a closed circuit in front of each end of the space between said windings.

4. A transformer including a core having a winding leg, two concentric windings surrounding said winding leg, one of said windings being formed in two spaced concentric sections, the other winding being interposed between the two sections of said first 85 winding and spaced therefrom, and conductive members extending along and close to the ends of each section of said sectional winding, said conductive members being connected around the outer edge of said core to form 90 closed circuits in front of the spaces between said windings. 80

In witness whereof, I have hereunto set my hand this 6th day of October, 1928.

GUGLIELMO CAMILLI.
